UNITED STATES PATENT OFFICE.

GEORGE M. FISCHER, OF AUSTIN, ILLINOIS, ASSIGNOR TO E. M. ELLIS, OF MEMPHIS, TENNESSEE.

DESIGN FOR AN URN.

40,259.

Specification for Design. **Patented Sept. 14, 1909.**

Application filed February 8, 1909. Serial No. 476,860. Term of patent 14 years.

To all whom it may concern:

Be it known that I, GEORGE M. FISCHER, a citizen of the United States, residing at Austin, in the county of Cook and State of Illinois, have invented a new, original, and ornamental Design for an Urn, of which the following is a specification, reference being had to the accompanying drawing, forming part thereof.

The figure is an elevation of an urn showing my new design.

I claim:

The ornamental design for an urn as shown.

GEORGE M. FISCHER.
